DESIGN FOR A SIGN

John Ruskin Tilton, Waterloo, Ontario, and
Alfred Braun, Kitchener, Ontario, Canada

Application October 19, 1937, Serial No. 72,312
In Canada June 19, 1937

Term of patent 7 years

To all whom it may concern:

Be it known that we, John Ruskin Tilton and Alfred Braun, respectively, a subject of the King of Great Britain, and a citizen of the German Empire, residing at, respectively, the town of Waterloo, in the county of Waterloo, and the city of Hamilton, in the county of Wentworth, both in the Province of Ontario, Canada, have invented a new, original, and ornamental Design for a Sign, of which the following is a specification, reference being had to the accompanying drawing, forming part thereof.

Fig. 1 is an elevational view of a sign, showing our new design, and

Fig. 2 is a top plan view thereof.

We claim:

The ornamental design for a sign, as shown.

JOHN RUSKIN TILTON.
ALFRED BRAUN.
